UNITED STATES PATENT OFFICE

167,515

SUPPORTING STRUCTURE FOR AN OVER- HEAD TWO-LANE TRACKWAY

Ayres C. Houghtelling, Washington, D. C., as
signor to International Railplane Corporation,
Nassau, Bahamas, a corporation of Panama

Application August 22, 1951, Serial No. 16,406

Term of patent 14 years

(Cl. D41—1)

To all whom it may concern:

Be it known that I, Ayres C. Houghtelling, a citizen of the United States and a resident of Wardman Park, Washington, D. C., have invented a new, original, and ornamental Design for a Supporting Structure for an Overhead Two-Lane Trackway, of which the following is a specification, reference being had to the accompanying drawing, forming a part hereof.

Fig. 1 is a perspective view of a supporting structure for an overhead two-lane trackway, showing my new design;

Fig. 2 is another perspective view from the opposite end as shown in Fig. 1; and

Fig. 3 is a front elevation thereof.

I claim:

The ornamental design for a supporting struc-

ture for an overhead two-lane trackway, as shown.

AYRES C. HOUGHTELLING.
